CARD HOLDER FOR ATTACHMENT TO BRAS AND THE LIKE

Joan M. Clark, 1517 W. 35th Place,
Los Angeles, Calif. 90018

Filed Mar. 20, 1975, Ser. No. 560,297

Term of patent 14 years

Int. Cl. D2—07

U.S. Cl. D2—400

Fig. 1

Fig. 5

Fig. 1

Fig. 3

Fig. 4

Fig. 2

Fig. 6

FIG. 1 is a perspective view of a card holder for attachment to bras and the like showing my new design;

FIG. 2 is a front elevation view thereof;

FIG. 3 is a rear elevation view thereof;

FIG. 4 is a left side elevation view thereof;

FIG. 5 is a top view thereof; and

FIG. 6 is a bottom view thereof.

I claim:

The ornamental design for a card holder for attachment to bras and the like, substantially as shown.
